UNITED STATES PATENT OFFICE.

NAZAIRE DEMERS, OF MANCHESTER, NEW HAMPSHIRE.

HAND-THREADING SHUTTLE.

1,104,416.

Specification of Letters Patent. Patented July 21, 1914.

Application filed April 12, 1913. Serial No. 760,763.

To all whom it may concern:

Be it known that I, NAZAIRE DEMERS, citizen of the United States, residing at Manchester, in the county of Hillsboro and State 5 of New Hampshire, have invented new and useful Improvements in Hand-Threading Shuttles, of which the following is a specification.

My invention pertains to shuttles and 10 more particularly hand threading shuttles.

The object of the invention is to provide a hand-threading shuttle that is well-balanced and light in weight and one calculated to be quickly and inexpensively produced 15 and which embodies no parts liable to wear out after a short period of use or parts likely to interfere in any measure with the operation of a loom.

The invention also seeks to avoid undue 20 weakening of the shuttle body and to preclude casual unthreading of the shuttle.

To the attainment of the foregoing and other objects hereinafter set forth the invention consists in the peculiar construction, 25 novel combination of parts as hereinafter described and definitely claimed.

In the drawings, accompanying and forming part of this specification: Figure 1 is a plan of so much of a shuttle as is necessary to illustrate the preferred embodiment 30 of my invention. Fig. 2 is a front side elevation of the same. Fig. 3 is an inverted plan view. Fig. 4 is a transverse section taken in the plane indicated by the line 4—4 of Fig. 2. Fig. 5 is a section taken on the line 5—5 of Fig. 1. Fig. 6 is a section taken on the line 6—6 of Fig. 2 with some parts in elevation. Fig. 7 is a cross-section on line 7—7 of Fig. 1. Fig. 8 is a cross-section on 40 the line 8—8 of Fig. 2. Fig. 9 is a perspective of my novel friction spring. Fig. 10 is a perspective of the novel eye.

Similar numerals of reference designate 45 corresponding parts in all of the views of the drawings.

The shuttle body 1 is provided with the usual chamber 2 to receive a bobbin 3 and is otherwise of the ordinary well-known general construction.

50 In furtherance of my invention the shuttle body is provided in its upper side with a longitudinal channel 4 that extends about the proportional distance illustrated from the chamber 2 toward the tip of the body 55 and is of the depth shown in Figs. 4 and 8.

Arranged in a transverse aperture 5 that

intersects the inner portion of the channel 4 is a pin 6. This pin rests in the portion of the aperture between the channel 4 and the front side of the shuttle body, and has a sharp point disposed in the channel as shown. Consequently the pin is enabled to lock the thread in the channel 4. The said pin 6 is not essential to the successful practice of my invention though it is preferably 60 employed. Manifestly it can be adjusted as occasion demands through the medium of a thin nail or piece of wire introduced from either end of the aperture 5 as is necessary. When deemed expedient a screw 7 is embedded in the shuttle body 1 at a point adjacent the aperture 5 in order to lend increased strength to the body. Extending crosswise of the shuttle body is a bore 8 and in the said bore is fixed the eye 9 comprised in my invention and hereinafter specifically described. 75

Communicating with the forward end of the channel 4 and extending forwardly and diagonally outward therefrom to the forward side of the shuttle body is a slit 10, and formed in the forward side of the shuttle body and leading backwardly from the slit 10 to the eye 9 is a horizontal slit. Extending upwardly from the underside of the 80 shuttle body and intersecting the forward portion of the channel 4 is a vertical bore 12, Figs. 3, 5 and 7, and in the said bore 12 is positioned the friction spring 13 which constitutes an important feature of my invention. 85

As will be observed by reference to Fig. 6, the eye 9, which is preferably of metal, is arranged immediately in advance of the friction spring 13, and by comparison of 90 Figs. 6 and 10, it will be noted that the eye has a notch 14 in alignment with the channel 4 and also has a slot 15 that extends outwardly from the notch. Said slot 15 merges at its outer end into a V-shaped slot 16, and the outer portion of this latter extends to the end of the eye 9 at the front side of the shuttle body and is there open. 100

As will be observed by comparison of Figs. 7 and 9 my novel friction spring comprises 105 a loop 17 having its bight flared outwardly, and a loop 18 that extends upwardly from one end of the loop 17 and has its bight disposed at a right angle to that of the loop 17. It will also be observed by reference to Fig. 110 7 that the bights of both loops 17 and 18 are disposed at the upper end of the bore 12, and

that the bight of the loop 18 is arranged at a right angle to the length of the channel 4. It will further be noted by reference to Fig. 7 that the terminal of the loop 18 is arranged adjacent the rear side of the shuttle body 1. Both terminals of the friction spring are indicated by 19 and bear at their lower ends against the side wall of the bore 12, and by virtue of this and the resiliency of the spring 10 it will be manifest that there is no liability of the spring being casually displaced during the use of the shuttle. When, however, it is desired for any reason to remove the spring, the same can be readily accomplished 15 by introducing a suitable instrument and displacing the terminals of the spring from their complementary bearings. The eye 9 is arranged in the transverse bore 8 and is held in position and against casual displacement 20 by frictional contact, and this with the tubular end portion of the eye (see the right-hand end of Fig. 10) adjacent the rear side of the shuttle body. In the event of the eye working loose it can be removed 25 from the bore and a wood plug 30 forced into the tubular portion of the eye (Fig. 10) to expand the eye, and then the eye can be forced back into the shuttle body, or, if preferred, the wood plug 30 can be forced into 30 the tubular portion of the eye while the eye remains in the shuttle body. At this point I would have it understood that it is necessary to remove the friction spring 13 as a condition precedent to the removal of the 35 eye 9.

In threading the shuttle, the thread is pulled in the curved slit 10 and slips downwardly in the mouth of the friction spring—*i. e.*, between the bights of the two loops 40 thereof. This curves the thread and at the same time the thread slips down by the point of the pin 6 and deep under the said point. During the pulling of the thread in the slit 11 toward the eye 9, the thread slips in 45 around the point or apex of the slit 16 in the eye and drops under the point at the end of the said slit 16. With this done it is impossible to unthread the shuttle. It will also be noticed in this connection that in delivering 50 the thread balloons around the end of the bobbin and plays up and down in the entrance channel 4 and under the pin 6. It will also be noticed that considerable play space for the thread is afforded under the 55 pin 6, and by reference to Fig. 6 it will be seen that a portion of the friction spring 13 is in the same vertical plane as the notch 14 in the eye 9, and the thread turns sharply around the said spring portion and enters 60 the notch of the eye to the best advantage. When the filling is of such character that friction or tension is not necessary, the friction spring 13 can be removed whereupon the thread will turn around the lip at the 65 left-hand side of the notch 14 in the eye 9.

It will be gathered from the foregoing that my improvements are calculated to prevent accumulation of lint or waste in the throat of the shuttle.

While my novel shuttle is a hand-threading shuttle, I would have it understood that the eye 9 and the friction spring 13 are susceptible of being used to advantage in a self-threading shuttle.

In the use of the shuttle, the thread has 75 considerable space to play at 35, Fig. 5, under the pin 6, and the friction spring branch holds the tension of the thread to prevent the thread from kinking or slackening the instant that the shuttle dwells, and further 80 that the shape of the slot in the eye at 16 allows the thread to play.

Having described my invention, what I claim and desire to secure by Letters-Patent, is:

1. The combination of a shuttle body having a chamber and a channel extending longitudinally from said chamber toward its tip and also having a transverse aperture that intersects the inner portion of said channel and extends between opposite sides of the body, and further having a vertical bore that extends between its lower side and said channel, a bore extending between the forward and rear sides of the body, a slit extending forwardly and diagonally outward from said channel to the forward side of the body, and a slit in said forward side and leading backwardly from the first-named slit to the second-named bore; a pin disposed 100 and adjustable endwise in the said transverse aperture and having its inner end arranged in the said channel; a tension device arranged in said vertical bore of the body and having a mouth disposed in alinement with the channel; and an eye arranged in the second-named bore of the body and communicating with the last-named slit of the body and also communicating with the channel and the tension device. 110

2. The combination of a shuttle body having a chamber and a longitudinal channel extending from the chamber toward a tip of the body and also having a vertical bore extending upwardly from its lower side and communicating with the channel; and a friction spring secured in the said vertical bore and comprising a loop having on its uppermost portion a bight that is flared toward one side of the body, and a loop having at its uppermost portion a bight that is disposed at a right angle to the first-named bight and has its inner leg inclined upwardly and outwardly. 115

3. The combination of a shuttle body having a chamber and a longitudinal channel extending from the chamber toward a tip of the body and also having a vertical bore extending upwardly from its lower side and communicating with the channel, a trans- 125

verse bore, and diagonal and longitudinal slits connecting the channel and the transverse bore; a transverse eye arranged in said transverse bore and having a notch communicating with the channel in the body and also having a tortuous slit extending outwardly from the notch to its delivery end; and a friction spring secured in the said vertical bore and comprising a loop having on its uppermost portion a bight that is flared toward one side of the body, and a loop having on its uppermost portion a bight that

is disposed at a right angle to the first-named bight and has its inner leg inclined upwardly and outwardly; said uppermost 15 portions of the loops forming a mouth, for the purpose set forth.

In testimony whereof I have hereunto set my hand in presence of two subscribing witnesses.

NAZAIRE DEMERS.
